(57) CLAIM

The ornamental design for an electrical power connector, as shown and described.

DESCRIPTION

FIG. 1 is a top, left, front perspective view of an electrical power connector according to a first embodiment of our new design;

FIG. 2 is a bottom, right, rear perspective view thereof;

FIG. 3 is a bottom, right, front perspective view thereof;

FIG. 4 is a top, left, rear perspective view thereof;

FIG. 5 is a top, right, front perspective view thereof;

FIG. 6 is a top, right, rear perspective view thereof;

FIG. 7 is a front elevation view thereof;

FIG. 8 is a rear elevation view thereof;

FIG. 9 is a top plan view thereof;

FIG. 10 is a bottom plan view thereof;

FIG. 11 is a left side elevation view thereof;

FIG. 12 is a right side elevation view thereof;

FIG. 13 is a bottom, left, front perspective view of a second embodiment thereof;

FIG. 14 is a top, right, rear perspective view of FIG. 13;

FIG. 15 is a top, left, rear perspective view of FIG. 13;

FIG. 16 is a top, left, front perspective view of FIG. 13;

FIG. 17 is another top, left, front perspective view of FIG.

13;

FIG. 18 is another top, right, rear perspective view of FIG. 13;

FIG. 19 is a top plan view of FIG. 13;

FIG. 20 is a bottom plan view of FIG. 13;

FIG. 21 is a right side elevation view of FIG. 13;

FIG. 22 is a left side elevation view of FIG. 13;

FIG. 23 is a front elevation view of FIG. 13; and,

FIG. 24 is a rear elevation view of FIG. 13.
